(57) **CLAIM**

The ornamental design for a smoking storage container, as shown and described.

DESCRIPTION

FIG. 1 is an isometric view of a smoking storage container showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof; and,

FIG. 7 is a bottom plan view thereof showing my design. Broken lines around the interior top and bottom opening indicates that no portion of the interior is included in the claim design.
